ELECTROPLATING RACK

Max Stefan Schneider, Chicago, Ill.

Application February 23, 1946, Serial No. 649,706

1 Claim. (Cl. 211—113)

1

This invention relates to an electroplating rack, and more particularly to a rack having combined therewith an anode unit of adjustable characteristics.

In production plating it is preferred that racks having provision to hold a plurality of like articles be of a type capable of adjustment to accommodate articles of different shapes and sizes. Heretofore racks for that purpose have been provided with sets of brackets rigidly affixed to a main supporting bar, the distribution and spacing of the brackets being determined by the configuration of the articles being plated. However, this necessitates a specific rack for each lot being processed and a consequent large investment in racks which are not usable for other articles.

Racks having adjustable article supports have been used, but since rubber coating of racks is almost universal, the screws or clamps provided for adjustably securing the supports to the principal rack member damage the rubber coating and seriously detract from its protective function.

Moreover, in plating apertured articles it has been found that proper deposition on the internal surfaces is attained only when an additional anode is positioned within the aperture. Prior devices included racks having accessory anodes which were fabricated to suit each lot of parts being plated so that for different parts another set of accessory anodes had to be provided, all of which is expensive and slows production.

Having in view the aforesaid and other shortcomings of certain prior forms of apparatus, my invention has for a principal object the provision of a plating rack having adjustable article-supporting arms shiftable to selected positions on the principal supporting bar without damage to the rubbery coating thereon.

Another principal object is to provide in an electroplating rack an anode structure adapted to be supported on the main bar of the rack, and having a plurality of anodes, one individual to each of a plurality of identical articles but adjustable to suit the requirements of another plurality of like articles dissimilar to said other plurality.

A further object is to provide an article-supporting member securable to the main supporting bar of a plating rack without the use of screws or other elements likely to injure the rubbery coating, the member including a U-shaped resilient portion adapted to be clamped on the rubbery surface without the use of tools

2

and instantaneously shiftable with respect to the main bar aforesaid.

Still another object is to provide an adjustable anode structure which may be readily detached from the main rack bar when not required and to thus permit the rack to be used for articles not requiring the accessory anode, the structure including finger-operated clamps engageable with the main bar.

In carrying out my invention in one form I provide a principal body member having means for supporting the rack on the bus bar of the electroplating tank, and carrying a plurality of adjustably secured, transversely disposed article supports, the supports having two opposed arms extending from a central saddle having means for securing the support to the body member. In article-clamping relation to each of the aforesaid supports is another two-armed clamping member of resilient metal having a U-shaped centrally disposed portion adapted to pinch the rubbery coating of the body member for adjustably securing the clamping member. Supported, as by clamps, on the body member is the adjustable anode structure including a framework carrying a plurality of rods of a selected diameter adapted to be positioned in an aperture of each of the articles to be plated, each rod being adjustable transversely in two perpendicular directions and the entire framework being adjustable vertically.

For a more complete understanding of the invention, reference should now be had to the drawing, in which:

Fig. 1 is a front elevational view of the rack including the adjustable anode structure with certain repeated portions omitted;

Fig. 2 is a side elevational detail of the upper portion of the rack and anode structure;

Fig. 3 is a side elevational detail of the lower portion of the rack and anode structure;

Fig. 4 is a cross-sectional view taken in the plane represented by the line 4—4 of Fig. 1; and

Fig. 5 is a cross-sectional view taken in the plane represented by the line 5—5 of Fig. 1.

Now referring to the drawing, I have shown a rack comprising a vertically disposed, elongated, principal body member 10 having a metallic core 11 of any suitable cross section, e. g., flat oval as shown, and covered with a rubbery coating 12 to inhibit deposit of plating metal thereon as is well known in the art. At its upper extremity the body member 10 is free of coating and receives in face-to-face relation with the core 11 a metallic rack-suspending hook 13

for carrying the rack as a whole upon the bus bar (not shown) of the electroplating tank. To align core 11 and hook 13 the latter may terminate in a bifurcated end 14, the two parts of which overlap the edges of the core 11; and for securing core 11 and hook 13, there is provided a U-shaped clamp 15 including a threaded tightening member 16 serving also as a handle for the rack whereby the body portion thereof may be immersed in or removed from the electrolyte.

The rack of the invention is primarily intended for production runs, i. e., the holding of a plurality of identical articles. Accordingly the body 10 is provided with a plurality of transverse, dual, article-supporting arms 21, for example as disclosed in my copending application Serial No. 593,441, filed May 12, 1945, and will therefore be referred to only briefly. Such arms 21 include a body-engaging portion 22 and two pairs of oppositely extending article-engaging fingers 23, each arm 21 being adjustably secured to the body 10. The fingers 22 may be of V-form for reception and securement of articles to be plated. As shown, the fingers 23 are coated with the rubbery material except where the articles are held.

Disposed above each arm 21 is a co-operative article-holding clamp 25 of resilient wire also coated with rubbery material. Each terminus of the clamps 25 may be undulate to provide a plurality of article-engaging notches 26 whereby certain forms of articles may be supported in a variety of planes with respect to the V-shaped ends of the arms 21 and as pointed out in my copending application Serial No. 649,707, filed February 23, 1946.

For adjustably securing the clamps 25 to the cushioned surface of the body 10, the same are made with a U-shaped central portion or saddle 27 resulting from appropriate bending of the wire upon itself, the conformation of the portion 27 being such as to substantially embrace the body 10 while disposing the notches 26 centrally of the fingers 23 (Fig. 4). Due to the resiliency of the wire forming the clamps 25, they may be manually sprung to open the bight of the saddle 27 to disengage a clamp from the body and to re-locate the same in another vertical position. Thus various sizes of articles may be interposed between the clamps 25 and fingers 23. Moreover, the resiliency of both said clamps and fingers enables more secure support of the articles.

In Figs. 1 and 3 I have shown, by way of example, tubular objects 31 supported by the rack for plating. To effect proper plating of the interior wall of the object, it is necessary, as previously pointed out, to insert thereinto an auxiliary anode connected to the source of electrical current, as will be understood in this art. Inasmuch as the article-supporting members are adjustable vertically, I have provided a novel form of anode structure now to be described.

Such structure includes a vertically disposed principal frame member 33 laterally spaced from and parallel to the body 10 and of any preferred cross section, for example, square as shown, and having a flattened upper extremity 34 apertured at 35 for reception of a terminal bolt (not shown) by which is attached the cable carrying current to the anode structure. At its upper and lower ends the member 33 has brackets 36 and 37, respectively, attached thereto as by welding or soldering. The brackets 36 and 37 are bent and offset to extend transversely of the

body 10, and are provided with fibre shoes 38 and 39 (Fig. 5) appropriately notched to fit over the coating 12. A bearing plate 42 and thumbscrews 43 permit the shoes 38 and 39 to be drawn together, whereby the anode frame may be temporarily secured in selected vertical positions relatively to the body 10 to permit vertical location of the several anodes with respect to the articles being processed.

Extending laterally from two opposed faces of the member 33 (Fig. 4) and threadedly inserted therein is the plurality of pairs of rods 45 locked by nuts 46 against unintended loosening and to provide suitable electrical contact, there being a rod associated with each set of fingers 23. Slidably fitted over each rod 45 is a connector 47 provided with an aperture 48 therein. To secure the connectors 47 in selected positions longitudinally of the rods 45, the thumbscrews 51 are provided. Extending perpendicularly to the rods 45 is the plurality of anodes 52 passing through apertures 53 in the connectors 47 and variably secured therein by thumbscrews 54. Thus it will be noted that the anodes 52 are adjustable longitudinally in the connectors 47 and may be moved laterally to effect a variety of positions thereof. Moreover, the anodes 52 may occupy various angular positions about the rods 45. Additionally, the entire assembly of anodes 30 may be unitarily shifted vertically by manipulating the thumbscrews 43. It is within the contemplation of the invention to substitute for the threaded junctions of the rods 45 with the member 33 connectors similar to connectors 47 for allowing independent adjustment of the rods 35 vertically as well as angularly about the axis of the member 33.

Accordingly, apertured articles may be supported in a position best adapted for insertion 40 of the anodes, and the anodes adjusted to optimum position within the apertures, for example in alignment with the longitudinal axis of the objects 31.

If the rack is to be used for articles not requiring the auxiliary anodes 52, the entire anode structure may be detached from the rack proper by freeing the clamps constituted by the shoes 38 and 39, thus reducing the weight of the rack assembly a substantial degree.

If desired, the supports 21 may be permanently attached to the body 10 in predetermined spaced-apart relation, or alternatively both supports 21 and arms 25 may be permanently so affixed, the resiliency of the members permitting simple engagement and disengagement of the articles held thereby.

While I have shown a particular embodiment of my invention, it will be understood, of course, that I do not wish to be limited thereto since 60 many modifications may be made, and I therefore contemplate by the appended claim to cover any such modifications as fall within the true spirit and scope of my invention.

Having thus described my invention, what I 65 claim and desire to secure by Letters Patent is:

An electroplating rack comprising in combination a single, elongated, substantially flat body member and a detachable elongated workpiece-engaging element connected thereto, said element including a resilient U-shaped portion adapted to grip said member, the legs of said portion extending over substantially the full widthwise extent of said member, and the interior widthwise dimension of said portion when 70 unstressed being less than the thickness of said

member, said element extending outwardly from the leg of said portion and disposed substantially perpendicularly thereto, said element having a plurality of workpiece-engaging V-shaped deformations adjacent each end thereof, and a second workpiece-engaging member having a U-shaped yoke clamped on to said body member and having oppositely disposed pairs of fingers, each pair extending substantially perpendicularly to the legs of the portion, and each said finger having a V-shaped deformation adapted to cooperate with the V-shaped deformations of said first mentioned element for supporting the workpieces in a selected position.

MAX STEFAN SCHNEIDER.
